CLAIM

The ornamental design for a graphical data display screen with graphical user interface, as shown and described.

DESCRIPTION

FIG. 1 is a front view of a first embodiment of a graphical data display screen with graphical user interface; and, FIG. 2 is a front view of a second embodiment thereof. The alternating long and short dashes which represent the display screen and the boundary of the claimed design form no part of the claimed design. The remaining broken lines represent elements of the graphical user interface and form no part of the claimed design.
